UNITED STATES PATENT OFFICE.

ROY H. BURGESS, OF GLEN ELLYN, ILLINOIS.

VERTICAL-FILE-FOLDING MACHINE.

Application filed July 1, 1926. Serial No. 119,847.

My present invention relates to vertical file folding machines, the invention being more particularly related to an improved tab cutting mechanism especially designed for use in connection with a vertical file folding machine of the type described and claimed in U. S. Letters Patent No. 1,574,789, granted to me on March 2, 1926, although my present improvements are not confined to that particular type of machine.

One of the main objects of my invention is to provide a simple and efficient die cutting mechanism for rapidly cutting differently positioned tabs on sets of vertical file folders; and a further object is to provide a mechanism of this character, so constructed and arranged that the roller means need not be adjusted or changed in order to produce tabs of any desired form or arrangement on the tops of the file folders, the means to this end including a novel construction of supporting and operating means whereby different sizes of die cutting wheel means may be employed in conjunction with the said roller means, thereby saving the expense of providing different roller means for each change in the form or arrangement of the tabs on a set of file folders.

Another object is to provide improved die cutting wheel means, so constructed and arranged that the die cutting blade may be readily removed from the wheel proper, to make provision either for the resharpening or the replacement of the die cutting blade as occasion requires.

A further object of my invention is to provide a die cutting blade which is adapted, upon each revolution thereof, to produce in the stock or web sheet a set of die cut folder tops having tabs so collated or coordinated that when the completed set of folders is filed vertically in a filing cabinet, all of the tops will be visible at a glance.

Other objects will appear hereinafter.

The invention consists in the combinations and arrangements of parts hereinafter described and claimed.

The invention will be best understood by reference to the accompanying drawings forming a part of this specification, and in which,

Fig. 1 represents a vertical section taken through a machine embodying my improve-

ments, this vertical section being taken so as to show my improvements in front elevation; 55

Fig. 2 is a vertical section taken on the line 2—2 of Fig. 1;

Fig. 3 is a vertical section taken on the line 3—3 of Fig. 1;

Fig. 4 represents a side elevational view 60 of a complete rotary cutting wheel;

Fig. 5 represents a central section through the rotary cutting wheel, this view being taken on the line 5—5 of Fig. 4;

Fig. 6 represents a plan view of a set of 65 die cut tops produced in the web sheet upon one revolution of the rotary die cutting wheel;

Fig. 7 represents a similar view, but showing the tabs on the component parts of the 70 set as formed in precisely the same positions;

Fig. 8 is a perspective view of a completed vertical file folder;

Fig. 9 is a side elevational view of the cutting blade as it appears when removed from the rotary die cutting wheel; 75

Fig. 10 is a cross section taken on the line 10—10 of Fig. 9;

Fig. 11 represents a side elevational view 80 of the rotary die cutting wheel with the blade and clamping ring removed;

Fig. 12 represents an edge view of the parts shown in Fig. 11; and

Fig. 13 is a side elevational view of the 85 clamping ring by which the cutting blade is secured upon the rotary die cutting wheel.

Referring with more particularity to the accompanying drawings, wherein I have illustrated by way of example the preferred 90 embodiment of my invention, it will be seen that the supporting frame work includes upright elements 14 in the top portions of which is rotatably mounted the axis 15 of backing roller 16 which is rotated through 95 the engagement therewith of a sheet 17 consisting of a web of relatively heavy manila paper of the type usually employed in producing vertical file folders. The roller 16, as already intimated, comprises a backing 100 for the traveling web sheet during the die cutting operations; and to this end said roller is provided with a highly tempered steel surface.

My invention comprehends the provision 105 of rotary cutting wheel means of various di-

2

mensions and adapted interchangeably to be employed in cooperation with the backing roller for producing in the traveling web sheet different sets of die cut folder tops; 5 and with this general object in view, I provide a main shaft 18 for carrying the rotary die cutting wheels of different sizes, means being provided for supporting the main shaft 18 for adjustment toward and away 10 from the backing roller in accordance with the particular size of rotary die cutting wheel selected to produce a given set of die cut tops in a web sheet, an adjustable transmission means also being provided for effecting the rotation of the main shaft 18 15 irrespective of its adjusted position.

The preferred means for operatively and adjustably supporting the shaft 18 comprises bearing blocks 19 through which may be slipped the opposite ends of the shaft 18, said bearing blocks being slidably mounted in vertically extending apertures 20 provided in guide elements 21, said bearing blocks 19 slidably fitting for vertical adjustment upon keys or ridges 22 projecting into the apertures 20 from the guide elements 21. The open top ends of the apertures 20 are closed by caps 23 which are secured as by means of screw bolts 24 upon the top ends 25 of the guide elements, said caps serving as stops for defining the upper terminal adjustments of the bearing blocks. Screw threaded through cross pieces 25, which define the lower ends of the apertures 20, are 30 adjusting screws 26 carrying heads 27, and coiled springs 28 are placed between the heads 27 and the bearing blocks 19. By this arrangement, the bearing blocks are both resiliently and adjustably supported in the 35 guide elements. For the support of the guide elements 21, the uprights 14 have projecting arms 29 attached thereto and these arms have vertically extending sleeve-like portions 30 and openings 31 in which said 40 guide elements have sliding fit and rack teeth 32 are provided on one side of the guide elements for engaging with pinions 33 carried by sleeves 34 pinned on shafts 35 rotatably mounted in the sleeve-like portions 45 30. For turning the pinions 33, I provide hand wheels 36 having hubs 37 secured to the shafts 35 and interlocking with the sleeves 34. Set screws 38, which are tapped through the sleeve-like portions 30, are 50 arranged to engage the guide elements 21 for securing them in the adjusted positions desired.

The adjustable transmission means whereby to operate the main shaft 18 in any given 55 position of adjustment comprises a sleeve 39 rotatably mounted in a cross piece 40, which connects the uprights 14, and a collar 41 on said sleeve which rests upon an anti-friction device 42 operatively seated in 60 a suitable socket 43 in said cross piece 40.

Telescoping in said sleeve is a shaft 44 having rack teeth 45 in engagement with the pinion 46. A sleeve 47, which is mounted in a casing 48, formed with the collar 41, supports the pinion 46 and is pinned on a 70 shaft 49 carrying a hand wheel 50 whereby the shaft 44 may be adjusted relatively to the sleeve 39 with which it rotates. Pinned to the top end of the shaft 44 is a bevel gear 51 adapted to engage with a suitable bevel gear 52 detachably secured to the main shaft 18. The sleeve 39, at its lower end, carries a bevel gear 53 in mesh with a bevel gear 54 on driving shaft 55 which is operated from any suitable source of power. The 80 transmission means is therefore adjustable in order that gears as 52 of different sizes may be employed in connection with the main shaft 18, so as to compensate as may be required for the employment of different 85 sizes of rotary die cutting wheels.

In the illustrated embodiment, the rotary die cutting wheel 56 comprises a wheel proper 57 formed with a circumferential flange 58 and provided with radially extending pin receiving slots 59. Surrounding the circumference of the wheel 57 and having pins 60 projecting into the pin receiving slots 59 is a rotary cutting blade 61 which is formed at certain interval-spaced positions with laterally offset cutting portions 62, there being countersinks 63 formed in the flange 58 for receiving said laterally offset cutting portions 62. For securing the blade in its circumferential seat upon the wheel and against the flange 58 thereon, I provide a clamping ring 64 adapted to fit flatwise upon the wheel 57 and to overlie the circular blade 61 and suitable bolt means 65 are taken through the clamping ring 64 and wheel 57, said bolt means being equipped with the usual nuts 66 whereby, as shown in Fig. 5, to secure the parts together.

Now, according to an important feature of my improvements, the circular blade 61 is of a circumferential dimension precisely equal to the composite lengths of a set of file folder tops as 67, 68, 69, 70 and 71, to be cut on the traveling web sheet 17; and where the file folder tops as 67 to 71 inclusive are to be provided with collated or coordinated tabs as 67' to 71', respectively, the laterally offset cutting portions 62 are produced on the circular blade in such relative positions that upon each revolution of the rotary die cutting wheel, a set of die cut tops 67 to 71 having collated tabs as 67' to 71', respectively, will be produced in the web sheet 17. After the web sheet through the cooperation of the rotary die cutting wheel and backing roller has had the file folder tops die cut thereon, any suitable folding and folder severing means, such as illustrated in my patent above referred to, may be employed 120 for folding the web sheet lengthwise and

then severing it along separating lines as 72 to produce vertical file folders 73, as illustrated in Fig. 8. Now, from what has been said, it will be understood, that rotary 5 die cutting wheels as 61 of different sizes may be applied to the main shaft 18 for cutting different sets of file folding tops in the web sheet. For instance, the rotary die cutting wheel may be reduced in size so that 10 upon each revolution it will die cut four file folder tops; or it may be still further reduced in circumferential dimension so that it will cut on each revolution but three file folder tops. Therefore, by providing means 15 for adjustably supporting the main shaft 18 and by providing adjustable transmission means for operating said shaft, interchangeable rotary die cutting wheels may be employed in connection with said shaft for 20 cutting different sets of file folder tops.

While I have illustrated and described the rotary cutting blade 61 as having the laterally offset portion 62 so spaced that the tabs will be formed in collated or coordinated 25 order as illustrated in Fig. 6, where the tabs 67' to 71' are shown as formed on the file folder tops at increasing distances from the left hand ends of the succeeding tops comprising the set, the cutting blade may also 30 be formed with the laterally offset cutting portions 62 so positioned that the tabs 74 shown on the die cut top 75 in the set illustrated in Fig. 7 are correspondingly positioned on the succeeding tops making up 35 the set.

For replacing a rotary die cutting wheel and also the power receiving bevel gear as 52, the main shaft is removed from its bearing blocks 19, this operation being accomplished by first removing the caps 23 and then lifting the bearing blocks 19 out of their guide elements 21. From the foregoing description, taken in connection with the accompanying drawings, it will be evident 45 that through the provisions made for employing rotary die cutting wheels of different sizes, different sets of file folder tops may be produced in the traveling web sheet without altering or changing the backing 50 roller 16.

While I have illustrated and described the preferred form of construction for carrying my invention into effect, this is capable of variation and modification without departing 55 from the spirit of the invention. I, therefore, do not wish to be limited to the precise details of construction set forth, but desire to avail myself of such variations and modifications as come within the scope of 60 the appended claims.

Having described my invention, what I claim as new and desire to secure by Letters Patent is:

1. Mechanism of the character set forth 65 including roller means for engaging and

backing a traveling web sheet; and rotatable wheel means resiliently and slidably supported for adjustment with a circular die cutting blade cooperating with said roller means to die cut said web sheet, said cutting 70 blade having interval-spaced laterally offset tab cutting edges thereon, substantially as described.

2. Mechanism of the character set forth 75 including roller means for engaging and backing a traveling web sheet; rotatable wheel means resiliently and slidably supported, said rotatable wheel means having a circular die cutting blade cooperating with said roller means to die cut said web sheet, 80 said cutting blade being formed with laterally offset tab cutting edges; and said cutting blade being of a circumference to produce a set of die cut tabs on each revolution thereof, substantially as described. 85

3. Mechanism of the character set forth 90 including roller means for engaging and backing a traveling web sheet; rotatable wheel means resiliently supported and horizontally slidably, said rotatable wheel means having a circular die cutting blade arranged to cooperate with said roller means to die cut said web sheet; laterally offset tab cutting edges on said blade which has a circumferential dimension sufficient to produce 95 a set of die cut tabs on each revolution thereof; and said laterally offset cutting edges being interval-spaced so as to produce a top on each die cut tab of the set, substantially as described. 100

4. Mechanism of the character set forth 105 including roller means for engaging and backing a traveling web sheet; rotatable wheel means resiliently supported and susceptible of horizontal and slidable adjustment, said rotatable wheel means having a circular die cutting blade arranged to cooperate with said roller means to die cut said web sheet, said blade being of a circumferential dimension sufficient to produce 110 a plurality of die cut tabs on each revolution thereof; laterally offset cutting edges formed at intervals on said blade to produce a tab on each die cut top; said laterally offset cutting edges being spaced so as to produce 115 the tabs in different positions on the die cut tops, substantially as described.

5. Mechanism of the character set forth 120 including roller means arranged to turn with a traveling web sheet engaged thereby, said roller serving as a die cutter backing for said sheet and having a highly tempered surface for such purpose; a rotatable shaft carrying a wheel, said wheel being resiliently 125 and slidably supported for adjustment; a circular die cutting blade on said wheel cooperating with said tempered surface to die cut said sheet; and interval-spaced laterally offset tab cutting portions on said blade co- 130

operating with said tempered surface, substantially as described.

6. In a machine of the character set forth, mechanism for applying a rotary cutter to 5 roller means for die cutting web sheets thereon comprising a shaft for supporting the rotary cutter; adjustable spring tensioned bearings slidably adjustable by gears and operatively supporting said shaft; a gear on 10 said shaft; a rotatable power receiving sleeve; a shaft telescoping in and rotatable with said sleeve and carrying a gear adapted to mesh with the first mentioned gear; and 15 means for adjusting the shaft telescoping in said sleeve, substantially as described.

7. In a machine of the character set forth, a main shaft provided with a gear; guide elements provided with rack teeth; bearing blocks arranged in said guide elements and 20 operatively supporting said main shaft; manually operated shafts with pinions engaging said rack teeth, for adjusting said 25 guide elements; in combination with means for driving said main shaft comprising a power receiving sleeve; a shaft telescoping in and rotatable with said sleeve and carrying a gear adapted to mesh with the gear on the main shaft, said telescoping shaft being 30 provided with rack teeth; and a manually operated shaft with a pinion engaging the rack teeth of said telescoping shaft for ad-

justing the telescoping shaft relatively to its sleeve, substantially as described.

8. In mechanism of the character set forth, the combination, with a web backing roller, 35 of a rotary circular cutting blade mounted on horizontally slideable and resiliently supported means, said blade co-operating with said roller for cutting a web mounted thereon, said blade having a laterally offset tab cutting edge portion, said offset edge portion having a straight section parallel to the extended lines of the main edge of the blade 40 for forming a straight edge on the tab.

9. In mechanism of the character set 45 forth, the combination, with a rotatably mounted web roller, of a die cutting blade adjacent said roller and adapted to co-operate with a web on said roller, a drive 50 shaft carrying said blade and adapted to actuate the same, journal bearings for said shaft, adjustable supporting means for said bearings adapted to shift the bearings for moving the shaft laterally toward and away 55 from said roller, and a power shaft substantially at right angles to said drive shaft, and geared to deliver power thereto, said power shaft being longitudinally, adjustably mounted.

In testimony whereof I have signed my name to this specification.

ROY H. BURGESS.
